UNITED STATES PATENT OFFICE

LUTHER D. LOVEKIN, OF ARDMORE, PENNSYLVANIA

PILOT-CONTROLLED VALVE

Application filed October 9, 1925. Serial No. 61,584.

My invention relates to gas pilots for automatic domestic water heaters of either storage or instantaneous type and to ovens, furnaces, house heaters, etc. using gaseous or liquid fuel.

5 The purpose of my invention is to protect against flow of gas through the main burner and, preferably, also through the pilot light when the pilot light is not burning.

10 A further purpose is to heat a thermostat from the pilot light and to control the gas supply for the main burner as well as for the pilot light from the thermostat.

15 A further purpose is to protect a pilot light-controlled thermostat from excessive heat from the main burner by air insulation, preferably providing cooling circulation of the air.

20 A further purpose is to provide for pilot valve gas feed through the thermostat chamber from the valve which is controlled to the pilot light and permissibly to control the amount of gas to the pilot during this passage.

25 Further purposes will appear in the specification and in the claims.

I prefer to illustrate my invention by one general form only, modified to suit different positions of use; selecting a form which is 30 practical, efficient and inexpensive and which at the same time well illustrate the principles of my invention.

Figure 1 is an elevation, partly broken away, showing an automatic storage type water heater to which my invention is applied.

Figures 2 and 3 are opposite end elevations of the structure seen in Figures 4 and 5.

40 Figures 4 and 5 are central longitudinal sections of a horizontal form of the structure embodying my invention showing the parts in different positions.

Figure 6 is an elevation, partly broken away, showing a vertical form of my invention applied to a burner.

45 Figure 7 is an elevation partly broken away showing a vertical form of the invention.

50 Figure 8 is a vertical central section showing a form of vertical pilot-valve-control

slightly different in gas distribution to the burner from the form in Figures 6 and 7.

Figures 9, 10, 11, 12 are sectional plan views of the structure seen in Figure 8, taken in the positions of section lines 9—9, 10—10, 11—11, 12—12.

Figures 1 and 7 are to smaller scale than the other figures.

In the drawings like numerals indicate like parts.

When the gas pressure is so far reduced upon the pilot light of an automatic gas-heated domestic water heater of the storage type that the pilot light goes out—as for example by street repairs upon the gas mains or where for any other reason the pilot goes out, the water becomes cold and the thermostat opens the main gas valve causing full flow of unconsumed gas which may asphyxiate the members of the household or cause an explosion and which, even if harmless in these ways by reason of passage up the chimney, wastes the gas. In the case of an instantaneous gas water heater the gas likewise flows freely and does damage or is merely wasted whenever opening of a faucet causes flow of water from the heater. My invention aims to protect in both cases by cutting off the supply of gas to the main burner and also desirably from the pilot light when the light goes out for any reason.

I have selected the storage type of heater for my illustration for the reason that the flow of gas in such a heater is more continuous than in the instantaneous type, causing a greater ultimate loss of gas notwithstanding that the rate of loss is not nearly so high and the danger not nearly so great in it while the gas is flowing as in the instantaneous type.

Describing first a horizontal form shown in Figures 1—5:

The invention is shown as applied to boiler 10 traversed by heating flue 11 for the hot gases from burners 12. The gas is supplied by pipe 13 passing through my pilot-controlled valve 14, thence to thermostatic valve 15 controlled by thermostat 16. Valves 17 and 18 are inserted in the gas pipe. The pilot gas supply at 51 is connected to the main gas pipe between the valves 14 and 15.

The pipes 20 and 21 supply inlet water and provide outlet for the heated water respectively, as is usual.

The pilot-controlled valve comprises a valve section, a thermostat section and a pilot valve section, rigidly connected and divided, where shown, for convenience of manufacture and assemblage.

Gas from the main comes in through pipe 10 13 and passes through the valve section, through valve opening 22 (Figures 4 and 5) to outlet pipe 23. The valve opening is closed by a valve 24 integral or otherwise, carried by a spindle 25 which has a seat at one end 15 in an opening 26 in the end 27 of thermostatic element 28, and at the opposite end terminates in a flange or button 29 held in position in any suitable manner, as by a nut 30. Between these ends the stem passes 20 through a stuffing box 31 in a closure 32 threaded into the valve section. The interior of the closure is provided with a seat for the spring 33, whose other end rests upon the valve.

25 The gland is screwed to position within the end of the casing and the packing is tightened within the gland by cover 34, the construction being such that the valve is spring pressed to its seat and that the forward end of the spindle, in the direction of pressure of the spring upon the spindle, is loosely connected with the end 27 of the thermostatic element. This leaves the spindle free to be pulled backwardly, against the 30 tension of the spring, without moving the thermostatic element. It may be held there by engagement with the button of an arm 35 pivoted at 36 and gravity-retracted.

The thermostat end 27 slides in a guide 40 and closure 37 fitting within a recess 38 in the rear end of a cup-shaped thermostat casing 39 and held within that recess by the threaded end 40 of the valve section which fits within the thread 41 in the casing. In 45 the form of my invention shown in Figures 8-11, where the gas is passed through the casing to the pilot light, there is no utility in forming a joint at this point, but in the form of Figures 1-7 it is desirable to additionally seal at this point, though this seal is not relied upon wholly to prevent gas leakage. In both the closure serves a guiding function.

The casing 39 is flanged at 42 for attachment to the wall 43 of the heater, from which it is heat-insulated at 44.

The thermostatic element 28 terminates at its forward end in a projection 45 fitting within a socket 46 connected with and supported by the casing and seals against packing 47 at the bottom of this socket. The packing rests upon flange 48.

The thermostat is shown as of the bellows type, and, of whatever type, expands and 65 contracts with heat transmitted to it, chiefly

through its terminals by conduction, from the pilot light parts and from the surrounding casing.

The pilot light support is carried by the casing 39 and is in close heat-conducting contact with it. They are shown as integral. The heat-conducting connection is further increased by metallic webs 49.

Upon the forward end of member 39 I mount the pilot light, feeding gas to it 75 through a tubular member 50 which is threaded at one end for connection of the pilot gas feed pipe 51 and at the other end is fitted to receive and hold the pilot light burner 52, usually of lava or similar material. The outlets 53 of this pilot light, shown as 80 two in number diverge to light the main burner to the best advantage, driving the gas out through an opening 54 between the member 50 and a projection 55 which are 85 bifurcated by the openings 54 and inevitably heating both of them. The heat is conducted from these terminal members 50 and 55 to the casing surrounding and in contact with the bellows, by the supporting metal, including fins or webs 49.

90 My invention contemplates heating the thermostatic element from the pilot light, in order to expand the thermostatic element to hold the valve open; but the delicacy of 95 thermostatic control which makes it possible for the pilot light to serve this purpose renders it highly desirable to protect the bellows and its surrounding structure somewhat from the much more intense heat of the main 100 burner upon that part of the structure which projects within the shell of the heater, shown at the left in Figures 4 and 5. I accomplish this by forming a protective shield 56 about 105 the end of the upper portion of my control valve upon that portion thereof which fits within the casing.

110 It will not be necessary for the cover 56 to enclose more than the upper part of the structure because this will itself shield the lower part from the heat of the burner chamber as well as from the actual heat of the burner and I have therefore shown the cover 56 as a mere shroud about the upper inner portion above the pilot light. However, in whatever 115 form this be constructed, I find that better results are obtained by spacing it from the metal of the casing 39 to provide a passage 57 open at both ends, so that the difference in temperature due to differing distance from the main burner and protection of one end by the shell of the heater result in flow of air through the passage and corresponding cooling both of the shroud and of the metal fitting beneath it. Part or all of the air from the passage 57 may include part or all of the air feeding the pilot light.

120 In operation if the pilot goes out the thermostatic element will cool much faster than the water if it be a storage type of heater, so 130

that the thermostatic element will contract to some such position as that shown in Figure 5 and the valve 22 will seat, closing passage of gas to the main burner as well as to the pilot light. Matters will remain in *statu quo* until the pilot light is relighted. If now the valve be opened and the pilot light be lighted, as soon as the valve stem is released the gas will be cut off from the pilot light and from the main burner and in the absence of one feature of my invention it would be necessary for the operator to hold the valve stem open until the thermostatic element has heated sufficiently to perform this function. If it were permanently propped open contraction of the thermostatic element would cease to be effective to permit spring closure of the valve.

When the valve is opened, therefore, the operator places the pivoted arm beneath the button where it is held by the closing pressure of the spring, the parts occupying the position in Figure 4. The closing pressure of the spring continues to hold the arm up to its duty until continued expansion of the thermostatic element causes the bottom of the socket 26 in the outer end of the thermostatic element to engage the end of the stem and continued expansion of the thermostatic element pushes the stem and thus the button beyond the position shown in Figure 4. The arm then drops away from the button leaving the stem free to follow the expansion and contractions of the thermostatic element and to close the valve with sufficient contraction of this element.

In the form shown in Figure 7 the general relation of the parts is identical with that shown in the preceding figures, with the difference, however, that because the thermostatic control valve is intended to be placed in vertical position some differences appear in additional weighting of the holding arm, construction of the shroud for directing flow of cooling air and the position and connection of the pilot light. The general assemblage is the same, the connections being such that the pilot-light-controlled valve cuts off flow of gas to the pilot light and to the main burner through the thermostatic control valve whereas the thermostatic control valve cuts off gas flow from the main burner but does not affect the pilot light.

Considering the structure from the bottom, the spindle, the gland construction, gas valve, thermostatic element and connections with the thermostatic element are intended to be identical with those shown in Figures 1-5.

The arm 35' is not as far off center in the vertical form as in the horizontal form and, as an additional precaution, has therefore been provided with additional weight in the form of a yoke. This yoke comprises bars 58 rigid with arm 35', straddling the lower end of the valve and weighted adjustably at 59 to give a desired additional off-center re-

leasing weight to insure that the arm 35' fall away from the position in Figure 7 when the thermostatic element has operated to push the spindle downwardly beyond the position shown in Figures 7 and 8.

The structure is mounted upon a different part of the wall 43 of the heater and in the mounting additional precaution against heat transfer from this wall is shown in Figure 8 in the complete insulation at 60 of the bolts 75 by which the flange 42 is held to the wall.

The protective shield 51' is here less of a shroud and more of a complete covering because of the greater exposure of the parts to the heat within the wall of the burner chamber. It is apertured at 61 for air inlet and at 62 for air outlet, opening being provided also for the pilot light and for screw 63 and gas connection 64.

The screw 63 is inserted for the purpose of holding the bellows member in position.

The gas connection 64 affords separate gas feed for the burner close to the burner. A slightly different form of the burner 52' is shown from that of the other figures and the burner is differently mounted being screwed into an opening coaxial with the sylphon element and protected by a cover 65 removable to give access to the burner.

In order to avoid the need of outside gas pipe connection for the pilot light and also to accommodate the adjustment of the flow of gas to this light I pass the gas from the compartment 66 in front of the valve, as considered in the direction of gas flow, through 95 the compartment containing the thermostatic element to the pilot burner. Obviously this may be done in various ways of which one convenient form is shown in Figure 8. I form an opening at 67 in the guide plate 37 and 100 curve the forward side of this plate at 68 so as to prevent closure of this opening by the rear end, near the lower end of the bellows. The curve at the forward end of this bellows compartment prevents the forward end of the 110 bellows from shutting off passage of the gas and communicates with a groove 70 which merges into a drilled hole 71 and transverse opening 72 by which the gas is led to the 115 passage 73 and into communication with the burner.

The screw 74 operates as a valve to close the opening of passage 72 partially to limit the flow or wholly to seal against flow, and at the same time gives an opening through which the transverse passage 72 may be controlled and the valve seat 75 may be faced.

My invention thus provides a setting device for initially holding the valve open, automatic release of this setting device, pilot light heating for thermostatic control of the entire gas supply, protection against excessive heating of the thermostat and interior flow with entire control over the pilot light gas supply.

It will be obvious that others skilled in 130

the art will see from my disclosure some of the other ways in which all or a part of the benefit of my invention may be secured without copying this form and it is my purpose therefore to cover herein all of these different forms which come within the reasonable spirit and scope of my invention.

Having thus described my invention, what I claim as new and desire to secure by Letters 10 Patent is:—

1. In a pilot-light-operated valve, a pilot light, a thermostatic element, metallic connections between adapted to cause expansion of the thermostatic element with heat from the pilot light, a socket connected with the thermotsatic element, a stem movable in said socket and adapted to be pushed by the bottom of the socket, a valve on the stem, a valve seat with which the valve is adapted to operate, spring retraction for the valve adapted normally to hold the valve against its seat and when the valve is open to hold the stem against the bottom of the socket, a pivoted arm adapted normally to swing away from the stem or into engagement with it and means on the stem engaged by the arm and adapted to hold the valve partly open until the stem is engaged by the bottom of the socket.
2. In a pilot-light-controlled valve, a pilot light, a thermostat in mechanical connection therewith, a spring-pressed valve and stem opened by movement of the thermostat and a cover about the connection between the pilot light and thermostat providing air passage for cooling air circulation between.
3. A pilot-light-controlled valvē comprising a pilot light, a thermostatic element heated therefrom and a valve controlled thereby, in combination with air-flow cooling mechanism exterior thereto protecting the portion thereof within the burner chamber from excessive heat.
4. In a pilot-light-valve-control, walls forming a heater chamber, and automatic pilot-light-controlled valve therefor and of which the pilot light and adjoining parts project within the casing, a thermostatic element heated by the pilot light and a cover for the portion projecting within the casing having air spacing between it and the pilot-light-controlled-valve to protect the pilot light and associated parts from excessive heating within the chamber, the air spaces being open near opposite ends to provide cooling air circulation.

5. In a pilot-light-control valve, walls forming a heater chamber, an automatic pilot light valve control of which the pilot light and adjoining parts project within the chamber, a thermostatic element heated by the pilot light and a cover for the portion projecting within the chamber having air spacing between it and the pilot light and adjoining parts to form a cooling passage to protect

them from excessive heating within the chamber.

6. In a pilot-light-controlled valve for controlling fuel supply to a main burner and to the pilot light, a pilot light, a metallic casing adjoining the pilot light, a thermostat element, a seat for the thermostat adapted to receive heat from the casing and to transmit heat to the thermostat whereby the thermostat will be heated by the pilot light, a valve stem axially in line with the thermostat and having a slip connection with the thermostat, a valve on the stem, a valve seat intermediate the length of the stem cooperating with the valve to control the supply of fuel to the main burner and to the pilot light, a spring surrounding the stem and tending to seat the valve to shut off the fuel to the main burner and to the pilot light and automatically disengaging means coacting with said stem to hold the valve in partly open position.
